UNITED STATES PATENT OFFICE

ARNOLD H. TOLD, OF CHICAGO, ILLINOIS, ASSIGNOR TO CHICAGO RAILWAY EQUIPMENT COMPANY, OF CHICAGO, ILLINOIS, A CORPORATION OF ILLINOIS

RAIL BRACE

Application filed January 16, 1931. Serial No. 509,086.

This invention relates to an improvement in the construction of a rail brace such as is used for bracing rails against side thrusts which tend to displace a rail laterally or to tip the rail.

The main objects of the invention are, to provide an improved form of rail brace which can practicably be made to fit the desired portions of a rail so as to effectively brace the rail, while at the same time avoiding excessive wear on either the brace or the rail as an incident to the normal relative movement therebetween; to provide such an improved rail brace which can be economically made, for instance, by drop forging; and, in general, it is the object of the invention to provide an improved brace of the type referred to.

Other objects and certain advantages of the invention will be understood by reference to the following specification and accompanying drawings (two sheets) in which two selected embodiments of the invention are illustrated.

In the drawings:

Fig. 1 is a side elevation of the improved brace, showing the same applied to a rail;

Fig. 2 is a plan of the improved brace;

Fig. 3 is a section on the line 3—3 of Fig. 1, and

Fig. 4 is a view similar to Fig. 1, but showing a modified construction.

Referring now to the drawings, a rail of conventional type is illustrated at 5, the same being seated on a tie 6. The rail may be secured to the tie 6 by spikes in the usual manner, or otherwise, the fastening means being omitted in the drawings, inasmuch as the invention herein involved is not concerned therewith.

Such rails as guard and stock rails, switch points, curved rails, and others, are subjected to considerable lateral thrusts which have a tendency to displace such rails laterally or to tip the same. For bracing such rails against such thrusts, various forms of braces are provided. In the drawings, the rail 5 represents any rail which requires bracing against lateral thrusts, and one form of my

improved brace is illustrated at 7 in Figs. 1, 2 and 3.

The brace 7 includes a base portion 8, preferably provided with notches, such as indicated at 9, in its opposite side edges, through which spikes such as indicated at 10 may be driven into the tie 6 for securely anchoring the brace. The brace also embodies a front portion 11, the lower part 12 of which is shaped to form a fillet-bearing surface adapted to fit or bear against the fillet 13 of the rail between the base flange 14 and web 15 thereof. A forward portion of the base 8 is offset upwardly, as indicated at 16, to overlie the base flange 14. The upper portion 17 of the front part of the brace is shaped to form a fillet-bearing surface which is adapted to fit or bear against the fillet 18 between the head 19 and web 15 of the rail substantially to the exclusion of other bearing engagement with the rail head. In the embodiment illustrated in Fig. 1, it will be observed that a portion of the web 15 of the rail adjacent each of the fillets 13 and 18 is also engaged by the front portion of the brace. However, it should be noted that the bottom surface of the rail head 19 is not engaged by the brace. A hollow strut 21 extends between the upwardly extending front portion 11 of the brace and the base part 8 thereof to rigidly support the said front portion 11 in its proper rail-engaging position. As will be understood from an inspection of Figs. 2 and 3, the hollow brace element 21 is of inverted, substantially U-shape or channel shape, the strut being considerably wider at its front end where it joins the front part 11 of the brace than at its rear end 22 where it is materially narrower. It will be understood that the fillet-bearing parts previously referred to are elongated and are substantially co-extensive in length with the width of the rail brace.

It will be understood that the various parts of the brace structure just described are formed integral with one another, preferably of malleable iron, and by any practicable process, such as forging, which may be economically practiced, while at the same time producing accurately fitting braces.

In the prior art, so far as known to me, braces of the general type herein referred to have been formed with a so-called fishing angle fit which contemplates an accurate fit between 5 the converging bottom surface 20 of the rail head and top surface 23 of the base flange 14. Such structures result in a considerable amount of wear on both the rail and brace because of the abrasive sliding action between 10 the rail and brace which normally occurs when a train passes over the braced rail. By eliminating this so-called fishing angle fit and providing a fit mainly in the rail fillets 13 and 18, I have found that the abrasive 15 or wearing effect of the normal relative movement between the brace and rail is largely eliminated so that the useful life of both the rail and the brace is materially prolonged. In other words, by eliminating the wedging 20 effect of the brace between the rail head and base flange, wear on the parts is materially reduced.

As indicated at 24, the front part of the brace intermediate its upper and lower fillet fitting parts is recessed. Such recess effects a saving in metal and consequent reduction in cost of the brace, while also avoiding the necessity of forming the entire front area of the brace part 11 to accurately fit the entire 30 area of the web 5. By relying on the reduced areas of contact or engagement between the brace and rail as shown, it is obviously much easier to produce an accurate fit between the reduced portions. It is found that such reduced contact areas may be formed with sufficient accuracy to constitute contact areas which are approximately 100% larger than the actual area of contact in the prior art type of braces. Obviously, such increased 35 contact area more effectively supports or braces the rail and more effectively resists wear on both the rail and brace.

In Fig. 4, the rail and its various parts referred to in connection with Figs. 1 to 3 inclusive are designated by the same reference characters, as is also the tie. The brace, which is of somewhat modified construction, is designated 25, and in general is of the same construction as the brace 7 above described. However, the top part 26 of the front portion 27 of the brace is shaped to fit only the fillet portion 18 of the rail to the exclusion of any material part of the web 5, while the lower portion 28 of the said front 35 part of the brace is similarly shaped to fit only the fillet 13 of the rail to the exclusion of both the adjacent part of the web and the top surface 23 of the base flange 14. The front of the brace is arched away from the 40 web 15 of the rail, as indicated at 29, and the base portion 16 is spaced upwardly from the top surface 23 of the rail base flange so that the only areas of contact occur at the fillets 13 and 18. This arrangement, while being 45 a greater departure from the more or less

standard practice and prior art construction, has substantially the same advantages there-over as those explained above in connection with the structure depicted in Figs. 1, 2 and 3. In the modified structure of Fig. 4, it is even easier to secure an accurate fit between the still further reduced areas of contact which are nevertheless sufficient for all practical purposes. In this modified construction, such limited wear as occurs between the base 16 of the brace and flange 14 of the 75 rail in the first described construction is practically eliminated.

I am aware that changes may be made in the above described structures without departing from the spirit of the invention, the scope of which should be determined by reference to the following claims, which should be construed as broadly as possible consistent with the state of the art.

I claim as my invention:

1. A rail brace of the class described, having a base part and a front part extending upwardly from said base part, the forward portion of said base part being adapted to fit over the base flange of a rail in spaced relation thereto and the portion of the brace at the junction of said base and front parts being formed to engage the fillet between the rail base flange and web portions, the upper portion of said front part being adapted to fit and engage the fillet between the head and web portions of the rail, and said front part being recessed intermediate said upper and lower fillet-engaging portions, the recess extending between said fillet-engaging portions and serving to prevent contacting of the front part of the brace with the web portion of the rail, and a hollow strut extending between said base part and front part for supporting the latter.

2. A rail brace of the class described, having a base part, a front part extending upwardly from the front edge of said base part, there being a bearing surface formed at the junction of said base and front parts for bearing against the fillet between the rail base flange and web portions, the upper portion of said front part being formed to clear the bottom surface of the rail head and to bear against the fillet between the head and web of the rail, said front part intermediate said upper and lower fillet-bearing portions being recessed to reduce the area of bearing contact between said front part and the web of the rail and to cause the thrust or load of the rail to be transmitted to the brace mainly through said fillet-bearing portions.

3. A rail brace of the class described, having a base part, a front part extending upwardly from the front edge of said base part, there being a bearing surface formed at the junction of said base and front parts for bearing against the fillet between the rail base flange and web portions, the upper por-

tion of said front part being formed to clear the bottom surface of the rail head and to bear against the fillet between the head and web of the rail, said front part being recessed 5 intermediate said upper and lower fillet-bearing portions, the recess extending between said fillet-bearing portions so as to cause the thrust or load of the rail to be transmitted to the brace through said fillet-bearing portions.

4. A rail brace of the class described, having a base part, and a front part extending upwardly from the front edge of said base part, the forward portion of said base part 15 being adapted to extend over the base flange of a rail in spaced relation thereto, and there being a bearing portion formed at said base and front parts to bear against the fillet between the rail base flange and web portions, 20 the upper portion of said front part being formed to clear the bottom surface of the rail head and to bear against the fillet between the head and web portions of the rail, and said front part being recessed intermediate 25 said upper and lower fillet-bearing portions, so as to reduce the area of bearing contact between said front part and the web of the rail, thereby to cause the thrust or load of the rail to be transmitted to the brace mainly through 30 said fillet bearing.

5. A rail brace of the class described, having a base part, and a front part extending upwardly from the front edge of said base part, the forward portion of said base part 35 being adapted to extend over the base flange of a rail in spaced relation thereto, and there being a bearing portion formed at the junction of said base and front parts to bear against the fillet between the rail base flange 40 and web portions, the upper portion of said front part being formed to clear the bottom surface of the rail head and to bear against the fillet between the head and web portions of the rail, and said lower part being recessed 45 intermediate said upper and lower fillet-bearing portions, the recess extending between said fillet-bearing portions so as to cause the thrust or load of the rail to be transmitted to the brace through said fillet-bearing portions.

ARNOLD H. TOLD.
